UNITED STATES PATENT OFFICE

137,942

DESIGN FOR A DOOR PLAQUE

Joseph P. Siewing, St. Louis, Mo.

Application October 6, 1943, Serial No. 111,280

Term of patent 3½ years

(Cl. D29—23)

To all whom it may concern:

Be it known that I, Joseph P. Siewing, a citizen of the United States of America, residing at St. Louis, State of Missouri, have invented a new, original, and ornamental Design for a Door Plaque, of which the following is a specification, reference being had to the accompanying drawing, forming a part thereof wherein:

I claim:

The ornamental design for a door plaque, as shown.

JOSEPH P. SIEWING.
